United States Patent Office

Des. 212,430

Patented Oct. 15, 1968

212,430

DOLL

Reuben B. Klammer, 245 S. Barrington,
Los Angeles, Calif. 90049

Filed Apr. 14, 1967, Ser. No. 6,636

Term of patent 14 years

(Cl. D34—4)

I claim:

The ornamental design for a doll, substantially as shown.
